HEATING APPARATUS

Robert H. Carson and Robert H. Carson, Jr.,
Chicago, Ill.

Application November 22, 1933, Serial No. 699,214

7 Claims. (Cl. 237—68)

Our invention relates to improvements in steam heating systems and similar apparatus.

Our invention relates more particularly to improvements in steam heating systems of the gravity, air line, or vacuum type.

One of the problems in dealing with low pressure steam heating plants has been: To relieve the system of air as rapidly as possible, and to return the condensation to the boiler with a minimum of friction and interference. When this has been accomplished, it permits the free flow of steam through the mains to fill the radiators, assuring full heating economy and efficiency. This is naturally a slow process without the aid of a vacuum pump or other mechanical devices.

In the early days of steam heating apparatus, there was no mechanical appliance that would perform this duty; consequently, it was necessary to create a high steam pressure in all heating apparatus in order to force the air in the mains and radiators through the air valve ports. Various devices have been utilized in the past for performing the same functions. The most successful of these devices are: The vacuum pump, the condensation pump, and receiving tank, which are generally recognized to be very efficient in connection with low pressure steam heating plants and operate both economically and efficiently during heating periods.

The principal object of the present invention is to provide improved means for effecting better circulation in the steam heating system.

A further object of the present invention is to provide an automatic mechanical device for producing the above mentioned result.

More particularly, an object of the invention is to provide improved means for removing air and non-condensable gases from steam heating systems and all other apparatus which require the removal of air or other gases therein in order that the system may function properly.

A further object of the present invention is to provide improved means for steam heating systems whereby a vacuum may be easily and frequently produced in the system in order to remove air and non-condensable gases therefrom.

A further object is to provide an improved mechanism of the type described capable of performing the acts mentioned and in addition thereto, returning the condensate to the source of supply, such as the boiler or the supply mains.

A further object is to provide an improved means of the type described capable of performing the acts explained on any of the systems mentioned much cheaper and more economically

than any other type of device at present on the market.

A further object of the present invention is to provide means of the type described capable of producing an extremely high vacuum at intervals throughout the entire period of operation of the system, and one which is accomplished either without the use of or by the use of a boiler independent of the main boiler of the system.

Other objects and advantages of the present invention will be more apparent from the following description wherein reference may be had to the accompanying sheets of drawings upon which:

Figure I is a diagrammatic view illustrating the apparatus which operates upon the system.

Figure II is a diagrammatic view illustrating the apparatus employed in connection with a compensating vacuum system.

Figure III is a diagrammatic view illustrating the employment of the apparatus in connection with an air-line system, and

Figure IV is a similar diagrammatic view showing the apparatus employed in connection with a one-pipe gravity steam system.

As shown in the drawings, we have illustrated a main boiler 3 of a heating plant from which a steam main 3a may extend upwardly to a plurality of radiators 6 connected thereto by suitable conduits 8. The main boiler 3 may utilize gas, oil, or coal for heating purposes, and in the embodiment of the invention shown in the drawings, we have shown a gas burner 10 provided with the usual pilot 12 which may be connected to the gas main 14 by means of a conduit 16. Adjacent the main boiler 3, we provide an auxiliary boiler unit 18 which is suitably connected to the fire box of the main boiler 3 by means of the passage-way 20. The unit 18 may be provided with a pair of comparatively small tank members 22 and 24, connected adjacent their lower ends by a conduit 26 and at an intermediate point by a larger conduit 28 provided to insure uniform circulation and heating in both tanks.

We provide a gas burner 30 below tank 22 provided with the usual pilot 31 and a conduit 32 extending to the conduit 16 which carries gas to the main boiler pilot 12. A gas pipe line 33 may extend from the burner 30 to the gas main 14. The pipe 33 may have a hand valve 34 therein and a pressure-stat valve 35 which has a conduit 36 connected to the interior of tank 24. A water pipe line 37 may extend from the water leg 38 to the lower end of tank 24 having the check valve 39 and the float valve 40 therein. The float

45

50

55

valve 40 is of the usual type actuated by a float 41 within the tank 24 and is adapted to shut off the supply of water when the water reaches the desired level in the tanks 22 and 24.

5 A baffle-plate 42, positioned horizontally within the unit 18, insures the use to its fullest extent of the heat produced by the burner 30 by reason of the manner in which it draws the flow of the heat upward and outwardly through conduit 20 into 10 the fire box of the main boiler 3.

A pair of outlet conduits, 43 and 44, are suitably connected to a vertical pipe line 45 which extends upwardly and is connected to the steam main 3a by means of a cross pipe 46. A check valve 47 in 15 the line 46 prevents the flow of steam through the line 46 into the steam main.

A by-pass 48 is formed around the check valve 47 and forms a connection with the steam main, however, through the pressure relief valve 49. A 20 branch 50 may extend outwardly from pipe line 45 and by means of suitable fittings, be connected to the upper end of a receiver tank 51. A 3-way valve 52 is positioned in the branch 50 for a purpose which will be hereinafter described. A conduit 53 may extend from the upper end of valve 52 and be connected to pipe line 48. The line 53 has a check valve 54 therein, as shown. The receiver tank 51 may preferably be cylindrical in shape and formed with a closed top and bottom. 25 The lower end may have a central tubular extension 55 connecting the same with a member 56 which has a chamber 57 formed therein. The lower end of member 56 may be connected to and supported by the water leg 38 previously described. The receiving tank 51 may be surrounded by a sheet metal shell 58 open at its lower end and closed at its upper end by a damper member 59. The damper member 59 is operated to open and shut by an expandible and contractible bellows member 60 connected thereto by a lever member 61. The bellows member 60 is supported upon an upright conduit 62 extending from the branch pipe 50.

Means for operating the 3-way valve 52 may 45 comprise the lever 63 connected by a link 64 to one side of a thermostatically operated bellows member 65 supported on a bracket 66 from the upper end of the receiver tank 51. A tube 67 communicating with the member 65 may extend 50 downwardly and terminate in a bulb member 68 and tube 67 which may be charged with a volatile fluid capable of expansion or contraction due to 55 thermostatic changes.

The bulb member 68 is adapted to be positioned 55 in the upper portion of chamber 57.

A stand-pipe 70 may be positioned within the water leg 38 and extend upwardly through chamber 57, extension 55, and into the interior of receiver tank 51, and have positioned at its upper 60 open end a horizontal plate member 71. This plate may be formed with a plurality of minute perforations and a flanged edge portion 72. The stand-pipe 70 may be connected at its lower end to a horizontal pipe 73 which has an extension 74 65 communicating with the lower end of a housing 75 within which the chamber 76 is formed. A similar extension 77 may connect to an upright pipe 78 which has an extension 79 connected to the side wall of chamber 56 adjacent its upper 70 end. The lower end of pipe 78 may be connected to a return pipe 79 which extends to the main boiler 3. Suitable check valves 80 and 81 are provided in the lines 73 and 77 and a check valve 82 is likewise provided in the return line 79 adjacent the main boiler 3. Both the pipes 74 and 75

79 may be controlled from the interior of the chambers 76 and 57 by suitable float valves 83 and 84.

The pipe line 77 may continue beyond its connection with the upright pipe 78 and be connected to the return line 79 beyond the upright pipe 78. A check valve 85 may be interposed in the line. The return lines 79 which come from the radiators 6 may be provided with suitable vacuum top air vents 90.

10 Similar air vent members 90 are positioned one in the upper wall of housing 56 and one on the upper end of a vertical pipe 91 which extends downwardly in the receiver tank 51. A water column pipe 92 extends from one side of the 15 housing 75 upwardly to a point above the water line of the main boiler 3.

10 The operation of the device as described in connection with the compensating vacuum system such as the one shown in Figure II, will now be 20 described:

Assuming that it is desired to begin the operation of the steam heating system, the pilots 12 and 31 may be lit before turning on the gas for the burners 10 and 30. Assuming further that sufficient water is contained in the main boiler 3 and auxiliary boilers 22 and 24, steam will soon be generated in all boilers. As soon as steam is generated, the steam will flow through the steam mains 3a to the various radiators and will force 30 all of the air in the system out through the vacuum top vents 90 positioned in the return lines 79. The steam will enter all of the radiators 6 in the system as soon as the temperature in the radiators rises. The thermostatic traps 95 mounted 35 at the outlet of each radiator will automatically close the radiator outlet.

During the interval in which the above has been accomplished, the auxiliary boilers 22 and 24 will have generated sufficient steam to fill and 40 drive out all of the air in the receiver tank 51. The steam flows through the upright pipe 45, cross pipe 50, and 3-way valve 52 which is normally in an open position as shown in Figure I. As soon as receiver tank 51 has been completely 45 filled with steam, the steam will pass through extension 55 to chamber 57 and serve to heat the bulb 68 to expand the volatile fluid therein which will pass upwardly through tube 67 and act upon bellows 65 to operate lever 63 to close 50 the valve 52, thus shutting off the supply of steam to receiver tank.

When valve 52 closes off the supply of steam 55 through line 50, it opens a passageway through pipe 53 to the steam main 3a, so that steam under pressure in the tank rushes up therethrough. In the event there is a slight vacuum in the steam line, the creating of a vacuum in the tank is thus expedited.

Assuming now that receiver tank 51 has been 60 filled with steam under pressure, steam from the receiver tank will produce a pressure in bellows member 60 which, by means of link 61, will swing the damper 59 to open a passageway in shell 58 to allow cold air to pass upwardly around the 65 receiver tank. The cooling of the receiver tank will immediately start the forming of a small vacuum due to the condensation of the steam when subjected to sub-atmospheric pressure. This will serve to draw condensate from the system through the stand-pipe 70 which will flow out upon the perforated plate 71 and trickle or rain downwardly through the steam in the receiver tank, causing a sudden reduction of the 70 temperature and volume, and as a consequence, 75

a very high vacuum will form in the receiver. This vacuum is sufficient to draw a large amount of condensate and air from the system through return line 79, upright 78, and stand-pipe 70 which will flow down extension 55 into chamber 57 and fill the same with liquid until the liquid reaches a sufficient level to raise the float valve 84 to allow the water to return to the boiler through pipe 78 and return line 79 when valve 52 is again opened and receiver tank 51 is filled with steam equal to or above that in main boiler 3.

The float valve 84, positioned in the top of chamber 57 will close the outlet through pipe 79 and allow sufficient water to stand in chamber 57 so that when pressure is applied to the surface thereof, the same will be forced down through pipe 96 and past check valve 97 to a chamber 76 of housing 75. This chamber 76 has a vent about half way from the top from which a water column pipe extends upwardly above the water line of the boiler. As water has been forced into chamber 76 by the action previously described, the float valve 83 will be opened and will remain open to allow the water to flow out through pipe 74 until the equalized pressure in the receiver tank 51 has dropped below that which forced the water into chamber 76.

As soon as the pressure in the receiver tank 51 drops below that of the air compressed in chamber 76 by reason of the introduction of the water therein, the air will move the water downwardly through check valve 80 and up through stand-pipe 70 to further cool the steam in the receiver. This cooling action has been found to cause about 25 inches of vacuum to suddenly form in the receiver and this sudden high vacuum causes another surge of water and condensate to rush through check valve 81 and stand-pipe 70 until chamber 57 has been filled with water to cover the bulb member 68, thereby causing a contraction in the volatile fluid and a movement of bellows 65 to operate valve 52 to the normal position shown in Figure 1.

When valve 52 is again moved to allow steam to enter tank 51, the condensate which may be in the tank is forced outwardly through pipe 79, 78, and into the main boiler 3 and any air which may be in the tank is exhausted through pipe 91 and valve 90. Air below the level of pipe 91 is driven out through air valve 90 located in the top of the housing 56. These valves are of the vacuum top type which allow air to be excluded therefrom but prevent the return of air, and are adapted to close at steam temperature.

It will be obvious from the foregoing description that as soon as the valve 52 has been returned to normal, the operation heretofore described will be repeated, thus providing a continuous production of high vacuum for withdrawing air and condensate from the system and applying this vacuum at intermittent intervals.

During the movement of lever 63 to open and shut valve 52 to allow steam to enter the receiver tank, there is a short interval when the valve is open to allow steam which may be in the line to flow upwardly through pipe 53 and pass check valve 54 into the steam main 3a. It will also be apparent that when a vacuum begins to form in the receiver tank 51, the bellows 60 will be contracted and operated to close the damper 59 to stop the circulation of air around the receiver. In the event that the steam pressure in the large boiler 3 rises above that in the auxiliary boilers 22 and 24, steam will pass

through pipe line 46, past check valve 47 and through pipe 50 into the receiver tank. Thus it can be seen that the receiver tank may be operated without the use of an independent or auxiliary boiler. In the event that the steam pressure is too high in the auxiliary boilers, it will be discharged into the steam main 3a through the relief valve 49.

In Figure III, we have illustrated in a diagrammatic manner the receiving tank and associated apparatus as applied to an air line heating system. In this type of system, the radiators 6 are usually connected to the steam main 3a by branches 6a which enter the radiator at a lower end thereof. The air return lines 6a usually extend from an inlet adjacent the upper end of the opposite side of the radiators and are each provided with thermostatic air vents 90a. The steam main 3a may extend throughout the system and have a return line 79 connected to conduit 77 which extends therefrom to the stand-pipe 70 in the receiver tank having a trap 85 similar to that shown in Figure I.

The return lines of steam main 3a are provided with air vents 90 at the points shown for the purpose of forcing air in the system outwardly, similar to the manner in which it is done in the previously described application. A thermostatic trap 95 is further provided in the line 77 for the purpose of preventing the withdrawal of steam from the mains 3a during a heating operation.

A conduit 6c may connect all of the air return lines with the line 77 entering the stand-pipe 70. The conduit 6c may have a suitable check valve 6d for the purpose of preventing air from being forced back from the receiver tank into the line.

With the air line system shown in Figure III, it will be obvious that the receiver tank operating at intervals will clearly increase the efficiency of the system by drawing the air through the lines 6c and by drawing the condensate which may form in the main 3a into the receiver tank through the line 77. It will further be obvious that by the use of the receiver tank mechanism, radiators may be placed below the water level of the water in the boiler, as the vacuum which is caused in the receiver tank will obviously be capable of drawing all condensate which may be in the pipes into the receiver tank, thus clearing the system and allowing the efficient circulation of steam.

In Figure IV we have illustrated the application of our improved apparatus to a one-pipe gravity system. In the drawings the steam main 3a may extend from the boiler 3 and have branches 6a extending to the individual radiators 6. Each of the radiators is provided with a suitable air vent 90 adjacent the upper end thereof through which the air that may be in the radiators or the mains is normally expelled. One leg of a return line 79 may extend from the steam main 3a and enter a line 79a which is suitably connected to line 77 that communicates with stand-pipe 70 and the other leg 79b may also be suitably connected as shown in the drawings.

Each of the return lines 79a and 79b are provided with air vents 90 at a point above the water level of boiler 3. A thermostatic trap 95 which closes under steam temperature is also interposed in the line 77 in this type of installation.

The purpose of utilizing our improved apparatus in connection with a one-pipe gravity system is to speed up the operation thereof, assist in drawing the air and condensate out of the system, 75

and has been found particularly useful where mains such as the steam main 3a have been sagged or bent around beams or other obstacles in a building, and have thus formed pockets which 5 it has been impossible to empty with the apparatus used in the past.

It is further evident that by creating a vacuum in the manner described, radiators may be placed below the water level of the boiler and condensate 10 and air will be drawn from them as easily and quickly as from any other part of the system.

While we have illustrated and described our apparatus with particular references to the systems discussed, it will be apparent that the apparatus 15 may be equally well applied to any other system or systems at present known or which may be devised, and we desire it to be clearly understood that we do not wish to be limited to the particular use shown nor to the exact details employed in the apparatus as described.

For example, it will be apparent that the shell 58, together with the bellows 60 and damper 59, may be omitted and the apparatus will function equally well as with the use of the parts mentioned. It will be further obvious that while 25 operation of the apparatus is quickened by the use of the auxiliary boilers mentioned, that the same may be omitted and the device will still function to perform the objects thereof.

30 What we desire to secure and protect by Letters Patent of the United States, is:

1. The combination with a steam heating system having a steam boiler, radiators, pipes thereto and return pipes therefrom, of an auxiliary 35 boiler, a receiver tank, a conduit therebetween, a thermostatically operated valve in said conduit, said valve responsive to the temperature within the shell and adapted to operate to close the valve upon an increase of temperature therein, a conduit 40 connected with the return line of said system having an upper end extending vertically into said receiver tank, a perforated plate secured to the upper end of said conduit, a shell enclosing said receiver tank, means connected with the inlet 45 side of the thermostatically operated valve in the conduit between said auxiliary boiler and said receiver tank for opening a passageway to allow cool air to circulate around said receiver tank to form a vacuum therein, said conduit connected 50 with the return line adapted to transmit the vacuum to said heating system to draw water and air therefrom.

2. Apparatus for employment with a steam heating system comprising a receiver tank, means 55 for providing steam therefor, means for closing off the source of steam when said tank is filled, a shell around said tank, means operated by the steam pressure in said tank for opening a vent in said shell to allow cool air to circulate around said tank, a vertical stand-pipe in said tank connected to the return line of said heating system, a horizontal perforated plate attached to the upper end thereof, said stand-pipe and plate arranged to draw condensate from the heating system by the low vacuum created by the cool air circulation and adapted to allow said condensate to sprinkle downwardly through the steam in said receiver tank to create a high vacuum therein to draw all the air and condensate from said system.

70 3. Apparatus for employment with a steam heating system comprising a receiver tank, means 55 for providing steam therefor, means for closing off the source of steam when said tank is filled, a shell around said tank, means operated by the

steam pressure in said tank for opening a vent in said shell to allow cool air to circulate around said tank, a vertical stand-pipe in said tank connected to the return line of said heating system, a horizontal perforated plate attached to the upper end thereof, said stand-pipe and plate arranged to draw condensate from the heating system by the low vacuum created by the cool air circulation and adapted to allow said condensate to sprinkle downwardly through the steam in said receiver tank to create a high vacuum therein to draw all the air and condensate from said system, and means associated with said tank for returning the condensate to the boiler of said heating system.

10 4. The combination with a steam heating system having a steam boiler, radiators, pipes thereto and return pipes therefrom of an auxiliary boiler, a receiver tank, a conduit therebetween, a thermostatically operated valve in said conduit, said valve adapted to close off the steam supply when said receiver tank is filled with steam, a conduit connected with the return line of said system having an upper end extending vertically into said receiver tank, a horizontal platform secured to the upper end of said conduit, means connected with the conduit between said auxiliary boiler and said receiver tank for drawing steam out of said receiver tank when said thermostatic valve is closed to form a vacuum therein and for 20 transmitting said vacuum to said heating system to draw water and air therefrom.

15 5. The combination with a steam heating system having a steam boiler, radiators, pipes thereto and return pipes therefrom of an auxiliary 35 boiler, a receiver tank, a conduit therebetween, a thermostatically operated valve in said conduit, said valve adapted to close off the steam supply when said receiver tank is filled with steam, a conduit connected with the return line of said 40 system having an upper end extending vertically into said receiver tank, a horizontal platform secured to the upper end of said conduit, means connecting said receiver tank with the heating system, said means comprising a check valve 45 opening towards said system, and a thermostatic valve arranged to open when the receiver is filled with steam, whereby steam in the receiver may be drawn into the heating system.

6. The combination with a steam heating system having a steam boiler, radiators, pipes thereto and return pipes therefrom of an auxiliary boiler, a receiver tank, a conduit therebetween, a thermostatically operated valve in said conduit, said valve adapted to close off the steam supply when said receiver tank is filled with steam, a conduit connected with the return line of said system having an upper end extending vertically into said receiver tank, a horizontal platform secured to the upper end of said conduit, a shell 60 enclosing said receiver tank, means connected with the conduit between said auxiliary boiler and said receiver tank for opening a passageway to allow cool air to circulate around said receiver tank only when said tank is filled with steam to 65 form a vacuum therein, said conduit associated with said receiver tank adapted to transmit said vacuum to said heating system to draw water and air therefrom and to employ the water drawn from said system to produce the vacuum for 70 operating the same.

7. The combination with a steam heating system having a steam boiler, radiators, pipes thereto and return pipes therefrom of an auxiliary boiler, a receiver tank, a conduit therebetween,

- a thermostatically operated valve in said conduit, said valve adapted to close off the steam supply when said receiver tank is filled with steam, a conduit connected with the return line of said system having an upper end extending vertically into said receiver tank, a perforated plate secured to the upper end of said conduit, a shell enclosing said receiver tank, means connected with the conduit between said auxiliary boiler and said receiver tank for opening a passageway to allow cool air to circulate around said receiver
- tank only when said tank is filled with steam to form a vacuum therein, said conduit associated with said receiver tank adapted to transmit said vacuum to said heating system to draw water and air therefrom and to employ the water drawn from said system to produce the vacuum for operating the same and return said water to said steam boiler and expel said air out of said system. 5
